UNITED STATES PATENT OFFICE.

JOSEF SCHISSLER, OF BADEN, NEAR VIENNA. AUSTRIA-HUNGARY.

RELAY FOR STRENGTHENING WEAK ELECTRIC CURRENTS.

1,086,942.

Specification of Letters Patent.

Patented Feb. 10, 1914.

Application filed September 20, 1911. Serial No. 650,380.

To all whom it may concern:

Be it known that I, Dr. JOSEF SCHISSLER, subject of the Emperor of Austria-Hungary, residing at Baden, near Vienna, Austria-Hungary, have invented certain new and useful Improvements in Relays for Strengthening Weak Electric Currents, of which the following is a specification.

This invention relates to relays or relay arrangements for strengthening weak undulating or alternating electric currents of that kind in which a variable resistance formed by the transition of a current between more or less loose contacts or electrodes and varying with the small movement of the electrodes is used for reinforcing the current undulations. Prior arrangements of the kind referred to are based on the combination of a microphone or telephone with said varying resistance, generally constituted by loose contacts or a second microphone-like structure, the oscillations of a diaphragm or the like due to spoken sounds or to variable magnetic action causing variations of said resistance and thereby fluctuations of the current passing. However, the fluctuations of currents obtained in the said known arrangements are not proportionate to the original current fluctuations, as the free oscillations of the movable parts interfere with the reproduction and thereby such proportionality is rendered impossible.

It is the object of the present invention to overcome these objections by providing an arrangement in which free oscillations cannot occur owing to the fact that the movable or oscillatory part which influences the varying resistance formed by the contacts or electrodes, (hereinafter termed "transitional resistance"), remains permanently under the influence of magnetic forces which by composition form a resultant force, while on the other hand, the oscillatory member itself is provided with magnetic forces and thereby always remains in a forced equilibrium due to the action of said exterior magnetic forces. The movement of said member is brought about by varying the magnetic resultant by means of the currents to be reinforced, and thus said movement is in complete accordance with the current variations and never exceeds the amount given by the variation of said resultant. In order to annul the movement

of the oscillatory member due to mere mechanical forces, as, for example, to its inherent elasticity or to its velocity, one of said magnetic forces is constituted by a powerful holding or braking electro-magnet 60 arranged in the axis of said member and thereby exercising its maximum action upon the member when said member is in its normal position, so that the velocity acquired is annihilated or braked as the said member 65 passes through the said normal position. To enable the oscillatory member to readily react and to enlarge the amplitudes obtained, the armature of the said member arranged opposite to the holding magnet is 70 cone-shaped, its larger mass being at the end removed from the magnet so that at an oscillation the greatest part of the magnetic flux, that is to say the central lines of force, will pass through the said thicker 75 part of the armature, the distance of which is somewhat greater than the point of the cone, the resultant of all magnetic forces being thereby altered with the movement of the oscillatory member, and thus a greater 80 amplitude may be obtained.

A further object of the invention is to provide means for exactly adjusting the amount of magnetic force in the oscillatory magnetic pole, which means consist in a 85 magnetic shunt provided at the permanent magnet to which the oscillatory member is secured. This adjustment is necessary for the starting of the arc or the sparks at the contacts or electrodes of the transitional resistance, as well as for the adjustment of the movement of the oscillatory part.

In order to render the strengthening action effectual, the local current on which the line currents have been superposed is in 95 addition passed through a strengthening coil which may be used either for producing fresh strengthened excitations of the same arc or for exciting the arc of a second relay.

The arrangement can be used both as a transmitter and as a receiver either by causing the sound waves to influence the spring magnet pole and through the latter the electric arc or by causing the elastic diaphragm 105 of a sound-box to be influenced by the arc and spring electrode.

Figures 1, 2 and 3 of the accompanying drawings diagrammatically illustrate three different arrangements of telephone relays

embodying this invention, in each case arranged for speaking and hearing simultaneously.

Referring to Fig. 1, 1 indicates a vertical standard or base to which the longer leg 3 of a permanent horseshoe magnet 2 is fixed. Rigidly secured to the shorter leg 4 of the magnet 2 is a flat blade 5 of spring steel having a broad bearing surface and carrying at its free end a soft iron armature 6 provided with electrical contacts 7 and 7'. The contacts 7 and 7' are conveniently formed as separate fittings to enable them to be made of material suitable for electric arc electrodes. The second or coating electrode is a duplex one and is constituted by two small plates 8 and 8' mounted on adjusting screws 9 and 9' respectively. With advantage the screws 9 and 9' are arranged eccentrically to the contacts 7 and 7' for the purpose of enabling fresh places to be frequently rendered operative in the formation of the electric arc. The screws 9 and 9' are each furnished with a milled head 10 and 10' respectively and with a milled lock-nut 11 and 11' respectively to enable them to be fixed in any desired position after adjustment. It will readily be understood that an approximate adjustment of the arc can be made by the screws and they accordingly form part of the adjusting arrangement. For the more delicate adjustment there is provided an iron bar 13 adapted to rub against both legs 3 and 4 of the magnet 2 and is adjustable angularly about a point 14 on the standard or base 1. The bar 13 is formed so as to embrace the magnet 2 and is furnished with a handle or grip 15. The magnetic shunt produced by the bar 13 influences the polarization of the magnet, that is to say it controls or determines the magnitude of the free magnetic masses in the spring 5 and thus enables the adjustment of the spring electrode to be effected with extreme delicacy and precision. The arc is influenced by the line electro-magnet 18 which may be constructed as a bell magnet, is carried by the longer leg 3 of the horseshoe magnet 2 and is traversed by the line currents that have to be strengthened; the line wires being accordingly connected to terminals 19 and 20. The regulating mechanism comprises an electro-magnet 29 and a holding magnet 16 which is arranged opposite to the armature 6. The electro-magnet 16 which may be constructed as a bell magnet or may be a permanent magnet or a combination of both, must also be so arranged as to be capable of adjustment and is conveniently adapted to be regulated in a vertical direction by means of a milled headed screw 17. A further regulation of the arc is effected at the same time by means of a strengthening device constituted by a strengthening or intensifying coil 21 on

which a secondary coil 22 is superposed according to requirement. The end portion or stem of the iron core 23 of this coil is for the purpose of finer adjustment formed with a screw-thread and is furnished with a milled head 26. A milled lock-nut 27 enables the core to be fixed in any desired position after adjustment. The telephone receiver 28 is connected either to the secondary coil 22 or is directly inserted in a local electric circuit which passes across the contacts of the coil 22. Instead of a telephone some other receiving instrument or a second relay may be inserted in the circuit. The position of the strengthening or intensifying coil 21 is like that of the line electro-magnet 18, not necessarily limited to any definite point opposite the spring blade 5. The apparatus comprises a regulating coil 29, hollow iron core 30, diaphragm 31 and sound funnel 32 which serves both for transforming the vibrations of speech and as a sound receiver. The funnel 32 is also arranged opposite the spring blade 5 which however is conveniently provided at this point with a soft iron armature 33. The coil 29 is also arranged opposite the spring blade 5 and is preferably carried on a movable bracket 24 adapted to slide on the standard or base-plate and be fixed in any desired position thereon by the screw 25, by which means a rough adjustment of the coil is effected. The diaphragm 31, which may be made of mica, glass, wood, parchment or the like, carries at its center, opposite the armature 33 of the spring blade 5 a soft iron armature 34 which may be of any suitable shape, but is preferably in the form of a flat cylinder or disk having an extension on one side the shape of which corresponds to that of the recess in the core 30 and which projects slightly into such recess. The iron core 30 as already stated, is hollow to allow of the passage of the sound vibrations. The local current is derived from a battery (which may be of the accumulator cell or other type) and is led from the terminal 35 by way of the standard 1 and magnet 2 to the spring blade 5 and contacts 7 and 7'. Upon the circuit being closed between the contacts 7' and 8' or as the case may be 7 and 8, the current flows through the screw 9' or the screw 9 respectively. From the screw 9' the current passes by way of the conductor 12 to the distributing point 39 and from there by way of the regulating coil 29 and the return conductor 38, shown by a dotted line, to the holding electro-magnet 16, thence by way of conductor 40 to the primary winding of the strengthening coil 21, thence to the terminal 41 and then back to the negative terminal 36 and the battery. From the screw 9 the current flows through the body of the bracket 24 to the distributing point 39 whence it fol-

lows the path just described back to the terminal 36 and the battery.

The arrangement shown in Fig. 2 only differs from that shown in Fig. 1 in that 5 the screw 9' and contact 8' corresponding thereto are dispensed with and that the strengthening coil 21 is arranged on the right hand side of the spring blade 5 on the bracket 24.

10 In the arrangement shown in Fig. 3 the spring blade 5 is fitted with a renewable holder for the arc contacts 7 and 7' which are arranged in the same way as the corresponding parts in Fig. 1. Instead of one 15 holding magnet 16, there are two such, 16' and 16'' which are connected in a kind of differential arrangement. The line electro-magnet 18 and strengthening coil 21 are in this case arranged directly opposite each 20 other. The path of the current is the same as before only that in this arrangement only the current regulating magnet 16'' is traversed by the local current, while the second or voltage regulating magnet 16' is 25 excited in accordance with the voltage drop at the arc at any given moment, as it is in a shunt. In this way the arc can be regulated in a uniform manner.

With a view to obtaining greater uniformity it is very advantageous to connect 30 in series and in advance of the arc or other gap or transitional resistance a steadyng resistance. A thin iron or other metal wire located in a hydrogen atmosphere is preferably employed for this purpose.

When it is desired that the relay should be actuated the local circuit is closed after the electrodes have been adjusted. The iron bar 13 is then swung about its horizontal 40 axis until it is brought into a position such that the spring magnet pole will be exactly so adjusted by the polarization obtaining at any given moment as to close the contact upon the slightest attraction being exerted 45 by the line electro-magnet 18. Upon this fine adjustment of the electrodes being attained, the iron bay 13 is fixed in place by the screw 14 and the apparatus is ready for work.

50 The arrangement shown in Fig. 1 works in such a manner that upon a very weak current being sent from the primary line to a microphone or the like through the line electro-magnet 18, the iron core of the latter becomes magnetized and attracts the spring blade 5. This causes contact to be made between the contacts 7' and 8' thereby closing the circuit and causing a bell that may be included in this circuit to sound. 55 Through the closing of this circuit the holding magnet 16 becomes a powerful electro-magnet that attracts the armature 6 and consequently the spring magnetic pole 5 and draws the spring blade out of its position 60 and produces a momentary contact between

7 and 8. This momentary contact is however at once broken through the action of the holding electro-magnet 16, which tends to hold the spring blade 5 in a vertical position, thereby causing an arc to be formed between the contacts 7 and 8, whereby the apparatus is adjusted for a given length of arc and consequently for a given voltage and such adjustment is maintained. For this purpose the position of the holding magnet must be very exactly determined in advance or this magnet must be provided with means for adjusting it laterally. The length of the arc is that determined by the resultant of the forces of the two electro-magnets 16 and 29 acting on the spring blade at an angle of 90° to each other. Moreover the pull on the spring blade or the state of tension thereof and consequently the frequency of its inherent or proper vibrations is determined by the attraction of the magnet 16 such attraction depending on one hand on the strength or amount of the force of magnetic attraction and on the other hand on the distance of the magnet from the armature that is to say upon its own adjustment. When resonance obtains between the transmitted vibrations and the inherent or proper vibrations of the spring magnet pole then the sensibility of the relay is at a maximum. 95 Once the arc is started the current fluctuations coming from the line will polarize the soft iron core of the line electro-magnet 18, whereupon the latter will alternately attract and release the spring magnet pole 5 thereby rhythmically increasing and diminishing the gap or transitional resistance between the two contacts (in the form of an electric arc in the example described) which in turn gives rise to analogous voltage fluctuations that traverse as such the primary winding of the strengthening coil 21, rhythmically influence the iron core thereof and consequently also attract the spring magnet pole 5 in the same rythm, this resulting in 100 the gap or transitional resistance being strongly influenced in a varying manner and consequently also in varying strengths of current. By this means the regulating magnet and the holding magnets are in turn also 105 more strongly excited and act to restore the apparatus to its original state. In this way 110 it is possible to obtain extremely strong current fluctuations that can be either transmitted directly to any kind of telephonic or telegraphic receiving apparatus or be employed to produce a strong induction current in the secondary winding of the strengthening or intensifying coil that may also be transmitted to a suitable receiving apparatus. These strengthened or intensified current fluctuations are perceived in the telephone 28 which may for instance be connected in the secondary winding 22. At the 115 same time moreover the rhythmic vibrations 120

of the spring magnet pole 5 (which, in some cases may be reinforced by the armature 33) act through their magnetism or purely mechanically on the flat iron cylinder or disk 34 arranged in the center of the diaphragm 31 made of mica, glass or the like. This iron cylinder or disk being located in the strong magnetic field of the coil 29 or it may be in the hollow magnetic iron core of the latter, is drawn more or less into the coil, thereby setting up vibrations in the diaphragm which are transmitted to the air and can accordingly be readily perceived.

When the apparatus is to be used as a telephonic transmitter the voice is directed into the speaking funnel 32. The vibrations of the air thus produced set up analogous vibrations in the diaphragm 31. The flat iron cylinder or disk 34 is thereby caused to participate in these vibrations and varies on one hand the magnetic field of the coil 29 and on the other hand directly influences both by magnetic attraction or in some purely mechanical way the spring magnet pole 5, thereby causing it to be attracted and released in the same rhythm so that the length of the arc is also varied. This variation in the length of the arc in turn brings about current and voltage fluctuations which also traverse the strengthening or intensifying coil 21 and consequently exert an enhanced attraction on the spring magnet pole 5 and thus give rise to fresh intensified current fluctuations. The induction currents thus set up in the secondary coil 22 are in this case not transmitted to the telephone 28 but to the line and to a similarly constructed apparatus in the receiving station. In the present case however the undulating currents set up by the use of an ordinary microphone might equally well be transmitted to the line electro-magnet 18.

In the arrangement illustrated in Fig. 2 the object attained by the modifications made therein and hereinbefore described is that the circuit is closed to start with and the arc started. The line currents traverse the coil 18 thereby polarizing the soft iron core of the latter and consequently causing the spring magnet pole 5 to be attracted and released in the same rhythm. By this means the arc formed between the contacts 7 and 8 is also varied in the same rhythmical manner. The current that has undergone variation in this way then traverses in the same way as in the arrangement of the apparatus shown in Fig. 1 the holding electromagnet 16, as well as the regulating coil 29 and strengthening or intensifying coil 21. The latter however is arranged on the right-hand side of the spring magnet pole 5 and acts to shorten the arc formed between the contacts 7 and 8 and thereby increase the strength of the current owing to the reduced

resistance. These intensified primary current fluctuations set up in the secondary winding 22 correspondingly intensified induction currents that are transmitted to the telephone 28 or any other instrument as may be desired. In other respects the action of the arrangement shown in Fig. 2 is the same as in the arrangement already described with reference to Fig. 1.

The working of the arrangement illustrated in Fig. 3 is substantially the same when acting as a transmitter as when acting as a receiver. Upon the current supply being introduced at the terminal 35 it flows by way of the standard 1 and the longer leg 3 of the permanent magnet 2 to the shorter leg 4 of such magnet, the spring magnet pole 5 and to contact 7 through the screw electrode 8 (which is normally adjusted to make contact by adjusting the lever 13), then through the primary winding of the strengthening coil 21, through coil 29 and through the regulating coil 16', which may alternatively be arranged on the other side of the spring magnet pole 5 in place of the coil 16' then by way of the conductor to the negative terminal 36. The circuit is thus closed and the regulating coil 16' which is connected in shunt and is wound with fine wire, is also traversed by a weak current passing by way of 7', 8' and 9'. This coil also might alternatively be arranged on the other side in place of the coil 16'. At this moment both coils 16' and 16'' will be acting to regulate the arc, the one connected to the gap or transitional resistance in series, regulating the current and the other namely the regulating coil 16' being arranged in shunt and wound with fine wire, regulating the voltage, the result being a regulation in respect of

$$\frac{\text{Voltage}}{\text{Current strength}} = \text{Resistance.}$$

By this arrangement, when the various parts are suitably arranged, the spring electrode 7 will be slightly drawn away from the contact 8 and the contact 7' will be moved toward the contact 8' thereby starting both arcs. The primary winding of the coil 21 is carried out in such a way that in the arrangement shown its magnetic core will repel or attract the spring magnet pole 5 according to the position relatively to the line electro-magnet 18. The two regulating coils act in the first place to adjust the arc to the normal length for the proper working of the apparatus. A suitably arranged holding magnet like the magnet 16 in Figs. 1 and 2 would answer the same purpose. Upon the primary line being connected up to the terminals 19, 20, the incoming weak current fluctuations will traverse the coil 18 and polarize its iron core, thus causing the armature of the spring magnet pole 5

to be attracted and released in the rhythm of the current fluctuations. As a result the length of the arc will also be varied rhythmically and the current fluctuations thereby caused will set up induction currents in the secondary winding 22 that either intensify or weaken the attraction and in addition set up strong vibrations in the telephone 28 which is included in the secondary circuit.

10 The arrangement of the coils and their construction are governed partly by purely physical and partly by constructional considerations, so that the accompanying diagrams only represent arrangements by way of example and various other arrangements would be possible without departure from the essential features of the invention. Thus for instance the arrangement shown in Fig. 2 might be arranged after the manner of

20 Fig. 1 and conversely so that any parts of the arrangements illustrated in Figs. 1, 2 and 3 might be combined together at will and also electrically connected in any desired manner. The arrangement may also be such that the adjusting screw 9 or 9' extends through the hollow iron core of the coil 18 and is insulated therefrom. Furthermore, the length of the arc can be adjusted according to requirement but will normally

30 never exceed fractions of a millimeter. The arrangements here illustrated can moreover be fitted in any existing telephone station as a current strengthening or intensifying apparatus. The incoming line currents to be strengthened or intensified traverse the winding of the coils 18 in Figs. 1, 2 and 3. The induction currents of the contact current are transmitted from the coil 22 (Fig. 1, 2 or 3) not to the telephone 28, but to

40 the terminal station, the telephone 28 being for this purpose put out of action as by an ordinary hook reversing switch. Accordingly upon the telephone being removed from the hook in the receiving station the message can only be received in such station. If, however, the message is intended for a further station the operation of hooking up the telephone again automatically reverses the connections onto the second or

50 secondary line. The whole arrangement may have connected in parallel to it an oscillating circuit comprising a controllable self-induction device and a variable capacity device and the arrangement may be used both for telephone work and ordinary and wireless telegraphy.

Claim.

1. In combination, means to form a magnetic circuit, an oscillatory member in said circuit, a stationary member forming with the oscillatory member a transitional resistance, an inverted frusto-conical armature on said oscillatory member, an electro-magnet coöperating with said armature in axial alignment therewith to damp the movements

of the oscillatory member, means to move the oscillatory member in accordance with line current fluctuations, and a local electric circuit including said member, said electro-magnet and the transitional resistance. 70

2. In combination, means to form a magnetic circuit, an oscillatory member in said magnetic circuit, a stationary member forming with the oscillatory member a transitional resistance, an inverted frusto-conical armature on said member in axial alignment therewith to damp the movements of the oscillatory member, means to control the magnetism through the oscillating member and thereby control its sensitiveness, means to operate the oscillatory member in accordance with line current fluctuations, and a local electric circuit including said member and said transitional resistance. 75

3. In combination, means to form a magnetic circuit, an oscillatory member and an electro-magnet to move said member in accordance with line current fluctuations both included in said magnetic circuit, a magnetic means to simultaneously control the 90 magnetism through said member and its moving means, a stationary member forming with the oscillatory member a transitional resistance, magnetic means to damp the movements of the oscillatory member, 95 and a local electric circuit including said member and resistance. 85

4. In combination, means to form a magnetic circuit, an oscillatory member in said circuit, a stationary member forming with the oscillatory member a transitional resistance, means to magnetically damp the movements of said member, means controlled by line current fluctuations for moving said oscillatory member, a local electric circuit 100 including said oscillatory member and said resistance, and transforming means also included in said electric circuit to produce strengthened current fluctuations corresponding to those in said electric circuit, 110 said transforming means including a primary winding in said electric circuit, a core adjustable to and from the oscillatory member and a secondary winding. 105

5. In combination, means to form a magnetic circuit, an oscillatory member forming part of said circuit, an electro-magnet controlled by line current fluctuations and a strengthening electro-magnet having a primary and a secondary winding, both magnets being in said magnetic circuit, a magnetic shunt whereby the polarization of said magnets and the magnetism through said member may be simultaneously controlled, a stationary adjustable member coöperating 120 with the oscillatory member to form a transitional resistance, an electro-magnet to damp the movements of said oscillatory member, and a local electric circuit including said oscillatory member, said damping 125 130

magnet, said resistance and said primary winding.

6. In combination, means to produce a magnetic circuit, an oscillatory member forming part of said circuit, a stationary member coöperating with the oscillatory member, a transitional resistance, intensifying means including a core adjustable to and from the oscillatory member and one or 10 more windings thereon, electro-magnetic means including a diaphragm-supported armature adjacent the oscillatory member, means to magnetically damp the movements of the oscillatory member and a local electric 15 circuit including said oscillatory member, said resistance, said intensifying means and said electro-magnetic means.

7. In a relay, a magnet having a long and a short leg, a steel spring secured to the 20 shorter leg, a soft iron armature at the lower end of said spring, electrical contacts on the armature, adjustable electrodes arranged to coöperate with said contacts to form arcs, an electro-magnet to damp the 25 movements of the spring, a diaphragm, an electro-magnetic device adjacent thereto, an armature on the diaphragm adjacent the spring, an electro-magnet adjacent the

spring controlled by line current fluctuations, a strengthening electro-magnet arranged adjacent said spring, a magnetic shunt to control the polarization of both the line-current-controlled magnet and the strengthening magnet, a local circuit including said spring, said resistance, said holding magnet, said electro-magnetic device and said strengthening magnet. 30 35

8. In a relay, the combination with a flat oscillatory member, contacts on opposite sides thereof, an armature on the member, 40 an electro-magnet on each side of the armature, adjustable electrodes coöperating with said contacts to form transitional resistance, a local electric circuit including said member, transitional resistance and one of said 45 magnets, and the other being in shunt circuit, whereby one of said magnets will regulate the current and the other the voltage in said local circuit.

In testimony whereof I have hereunto 50 set my hand in presence of two subscribing witnesses.
